US00D968088S

(12) **United States Design Patent** (10) **Patent No.:** **US D968,088 S**
(45) **Date of Patent:** **** Nov. 1, 2022**

(54) **DUFFEL BAG**(71) Applicant: **YETI Coolers, LLC**, Austin, TX (US)(72) Inventors: **Roy Joseph Seiders**, Austin, TX (US); **Erik Steven Larson**, Austin, TX (US); **Derek G. Sullivan**, Austin, TX (US); **Alex Baires**, Austin, TX (US); **Jeffrey Charles Munie**, Austin, TX (US)(73) Assignee: **YETI Coolers, LLC**, Austin, TX (US)(***) Term: **15 Years**(21) Appl. No.: **29/747,980**(22) Filed: **Aug. 26, 2020****Related U.S. Application Data**

(63) Continuation of application No. 29/695,005, filed on Jun. 14, 2019, now Pat. No. Des. 896,516, which is a continuation of application No. 29/639,767, filed on Mar. 8, 2018, now Pat. No. Des. 851,400.

(51) **LOC (13) Cl. .... 03-01**(52) **U.S. Cl.**USPC ..... **D3/289; D3/217**(58) **Field of Classification Search**

USPC D3/273, 276, 278, 283, 284, 285, 289, D3/290, 301, 900, 243, 245, 217, 901, D3/205; D7/607, 335, 601

CPC .. A45C 11/20; A45C 1/02; A45C 3/04; A45C 5/005

Primary Examiner — April Rivas

(74) *Attorney, Agent, or Firm* — Banner & Witcoff, Ltd.

(57) **CLAIM**

The ornamental design for a duffel bag, as shown and described.

DESCRIPTION

FIG. 1 is a top, front, right perspective view of a duffel bag showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines illustrate portions of the duffel bag or unclaimed stitching and form no part of the claimed design.

1 Claim, 6 Drawing Sheets
